UNITED STATES PATENT OFFICE

HOWARD H. SCHOTT, OF ROCHESTER, NEW YORK, ASSIGNOR TO ROBESON ROCHESTER CORPORATION, OF ROCHESTER, NEW YORK, A CORPORATION OF NEW YORK

DESIGN FOR A TEAPOT

Application filed October 3, 1929. Serial No. 32,936. Term of patent 7 years.

To all whom it may concern:

Be it known that I, HOWARD H. SCHOTT, a citizen of the United States, residing at Rochester, in the county of Monroe and State of New York, have invented a new, original, and ornamental Design for Tea-pots, of which the following is a specification, reference being had to the accompanying drawing, forming part thereof.

Fig. 1 is a side elevation, and Fig. 2 is a top plan view of a tea pot showing my new design.

I claim:

The ornamental design for a tea pot, as shown.

HOWARD H. SCHOTT.
